Inventor:
John L. Creveling

Attorney.

UNITED STATES PATENT OFFICE.

JOHN L. CREVELING, OF NEW YORK, N. Y.

GAS-LIGHTING APPARATUS.

SPECIFICATION forming part of Letters Patent No. 629,890, dated August 1, 1899.

Application filed July 30, 1898. Serial No. 687,290. (No model.)

To all whom it may concern:

Be it known that I, JOHN L. CREVELING, of New York, in the county of New York, State of New York, have invented certain new and 5 useful Improvements in Gas-Lighting Apparatus, of which the following is a complete specification, reference being had to the accompanying drawings.

The object of my invention is to produce 10 apparatus for lighthouses or beacons, for example, in which mechanism for producing a flash-light or other variable light is operated by the flow of gas to the burner.

In the accompanying drawings, Figure I is 15 a central vertical section, partially in elevation, of a gas-lighting apparatus embodying my invention. Fig. II is a bottom plan view of the revoluble frame detached, illustrating the frame-driving gears intermeshing, as in 20 operation.

Referring to the figures on the drawings, 1 represents a suitable support—as, for example, the floor or platform of a tower or beacon.

2 represents the outside casing of the lantern, which is preferably made of metal, as iron, and which supports the glass superstructure 3. The superstructure and the casing are rigidly united, as by a joint 4, and the casing is united to the platform 1, as by an 30 annular angle-iron base 5, whereby the combined structure is made practically air and water tight.

The superstructure 3 is surmounted by a suitable cover or roof 6, which is preferably 35 hinged or otherwise removably secured to the superstructure 3. As illustrated in the drawings, it is formed with a flanged rim 7, which overlaps the annular head 8 of the superstructure 3.

40 Within the casing 2 I provide a standard 9, secured to the floor 1, as by bolts 10. The standard is arched at its upper end and is provided and preferably incorporated with an annular grooved track 11, which, as upon anti-friction rollers or balls 12, carries the revoluble frame 13, which is provided with a grooved track 14, corresponding to the track 11, the balls 12 working in the opposing grooves in the tracks.

45 50 Within the space inclosed by the tracks 11 and 14 projects downwardly from the frame

13 a hollow cylindrical stud 15, to which is fixed a gear-wheel 16. The gear-wheel 16 (see Fig. II) meshes with the pinion 17, that is fixed to the end of a shaft 18 of a gas-meter 55 19. The meter 19 may be of any suitable and ordinary variety capable of causing the shaft 18 to revolve when gas passes through the meter. The meter mechanism, being such as is well known in the art, is not illustrated in detail, the exterior of the case only being shown. A meter of ordinary type is adopted as a suitable and convenient example of gas-actuated frame-driving mechanism and is employed in this connection specifically for the 60 purpose of imparting rotation to the frame 13.

The upper end of the shaft 18, adjacent to the pinion 17, works snugly in a suitably-fitted aperture provided for it in the standard 9 and is by that means supported in mesh with 70 the gear 16.

20 indicates a burner pipe or pillar which carries upon its upper end a burner or cluster of burners 21 and which is supported within the hollow of the stud 15 by the standard 9, 75 through which it communicates with the outlet-pipe 22 of the meter. The inlet-pipe 23 of the meter communicates through a pressure-regulator 24 with a supply-pipe 25, communicating with a source of gas-supply. (Not illustrated.) The pressure-regulator 24 may be of any desired type adapted to deliver the required flow of gas at a constant outlet-pressure regardless of the pressure of the inlet. The mechanism of pressure-regulators of this 85 class is old and familiar in the art and does not require detailed illustration. Its function specifically is to supply gas at a constant pressure to the pipe 23 from the pipe 25.

The revoluble frame 13 is adapted to carry 90 the means of producing through its revolutions the variable light which it is the object of my invention to produce. Such means, consisting, essentially, of an element which will at some point or points of the rotation of 95 the frame 13 intercept the rays of light from the burner is, for convenience of general designation denominated an “intercepting member.”

The form of embodiment of my invention 100 illustrated carries upon one side, as the intercepting member, a prism 26 and upon the

other side a counterweight 27; but a second prism may be substituted for the counterweight 27, or bull's-eyes, blank disks, or reflectors might be substituted for one or both 5 prisms or might be used in connection with one or both without departing from the principle of the apparatus illustrated.

28 indicates a lens that is hung by means of a frame 29 from the head 8, an annular lip 10 30 being provided in the head for the flanged end 31 of the frame 29.

32 indicates a flue for the discharge of the products of combustion from the burners 21 through a ventilator 33 in the top of the roof 15 6. It is secured in the disk-head 34 of the frame 29, as by screw-threads 35.

36 indicates a diaphragm which, joined at its base to the frame 29 and at its upper end with the ventilator 33, defines within the roof 20 6 distinct passages for the products of combustion and for the air supplied through suitable caps 37 in the roof for the support of combustion at the burners 21. The air supplied through the caps 37 is partially confined 25 under the roof around the diaphragm 36, being admitted through apertures 38 in the annular head 8. The diaphragm and other metallic parts above the burners 21 are heated by the passage of the products of combustion 30 from the burners through the flue 32, and by that means the inlet-air is heated before it reaches the burners 21.

The operation of my apparatus, briefly stated, is as follows: Gas under pressure flows 35 from the pipe 25 to the regulator 24, and thence at a constant and suitable pressure through the pipe 23 to the internal mechanism of the meter 19, whence it issues through the pipe 22 and pillar 20 to the burners 21, where it is ignited. As above set forth, in passing through 40 the meter 19 the flow of gas imparts rotation to the shaft 18, which by means of the intermeshing pinion 17 and gear 16 causes the frame 13 to revolve at a uniform velocity, the 45 uniformity of movement being provided by the constancy of flow of gas through the pipe 23, which is maintainable while a flame is supported at the burner 21. Through the rotation of the frame 13 the intercepting member— 50 for example, the prism 26—is caused to revolve about the lens and at regular intervals to pass between the eye of a stationary observer and the source of light. By this means when the prism is employed a powerful flash, common in lighthouse practice, 55 is produced.

The interval between the flashes may be diminished by the employment of a plurality of prisms. Other effects may be produced 60 by the substitution of other intercepting members for the prism illustrated.

What I claim is—

1. In gas-lighting apparatus for lighthouses or the like, the combination with a burner and means of communication with a 65 source of gas-supply, of a revoluble frame adapted to carry an intercepting member around the burner, and gas-actuated frame-driving mechanism in operative communication with the source of gas-supply, substantially as set forth.

2. In gas-lighting apparatus for lighthouses or the like, the combination with a suitable support, and revoluble frame thereon adapted to carry an intercepting member 75 around the burner of the lighting apparatus, of means of communication with a source of gas-supply, and gas-actuated frame-driving mechanism in operative communication with the source of gas-supply, substantially as set forth.

3. In gas-lighting apparatus for lighthouses or the like, the combination with a suitable support, and a revoluble frame carried thereon, adapted to carry an intercepting 85 member around the burner of the lighting apparatus, of means of communication with a source of gas-supply, gas-actuated frame-driving mechanism in operative communication with the source of gas-supply, and means 90 for maintaining a constant pressure of gas, substantially as set forth.

4. In gas-lighting apparatus for lighthouses or the like, the combination with a standard, burner thereon, and revoluble 95 frame adapted to carry an intercepting member around the burner, of means of communication with a source of gas-supply, gas-actuated frame-driving mechanism, including a shaft geared to the frame and in operative 100 communication with the source of gas-supply, substantially as set forth.

5. In lighting apparatus for lighthouses or the like, the combination with a draft and water proof structure adapted to inclose the 105 lighting apparatus, an annular head provided with apertures above said structure, and a roof surmounting the same, of a lens-supporting frame suspended from the head, and closing the space encircled by the head, a flue 110 carried in the lens-supporting frame, and a ventilator in the roof with which the flue communicates, a diaphragm between said frame and the ventilator, and air-inlet caps in the roof, all coöperating substantially as and for 115 the purpose specified.

In testimony of all which I have hereunto subscribed my name.

JOHN L. CREVELING.
